[57] CLAIM

The ornamental design for a task lighting fixture, as shown and described.

DESCRIPTION

FIG. 1 is a side elevational view of a task lighting fixture showing my new design;

FIG. 2 is a bottom plan view thereof;

FIG. 3 is a front elevational view thereof;

FIG. 4 is a bottom plan view thereof, the interior portion of the housing being rotated to an alternate position;

FIG. 5 is a bottom perspective view thereof;

FIG. 6 is a top plan view thereof.

The fluorescent tube and socket are shown in broken lines for illustrative purposes only.

FIG. 1

FIG. 2

FIG. 3

FIG. 4

FIG. 5

FIG. 6
